UNITED STATES PATENT OFFICE

HARRY R. HAYES, OF BROOKLYN, NEW YORK

DESIGN FOR A COMBINED AUTOMOBILE HOOD, RADIATOR, AND HEADLIGHT

Application filed August 9, 1932. Serial No. 44,557. Term of patent 14 years.

To all whom it may concern:

Be it known that I, HARRY R. HAYES, a citizen of the United States, residing at No. 901 73d Street, in the borough of Brooklyn, in the city of New York, in the county of Kings and State of New York, have invented a new, original, and ornamental Design for Combined Automobile Hood, Radiator, and Headlight, of which the following is a specification, reference being had to the accompanying drawing forming a part thereof.

Figure 1 is a front elevation.

Figure 2 is a side elevation, and

Figure 3 is a plan view from the top of the combined automobile hood, radiator and headlight, showing my new design.

I claim:

The ornamental design for a combined automobile hood, radiator, and headlight, as shown.

HARRY R. HAYES.
